US0D1019122S

(12) United States Design Patent (10) Patent No.: US D1,019,122 S
(45) Date of Patent: * Mar. 26, 2024

(54) BAG

(71) Applicant: Thule Sweden AB, Hillerstorp (SE)

(72) Inventor: Chris Grill, Longmont, CO (US)

(73) Assignee: Thule Sweden AB, Hillerstorp (SE)

() Term: 15 Years

(21) Appl. No.: 29/867,844

(22) Filed: Nov. 10, 2022

Related U.S. Application Data

(63) Continuation of application No. 29/776,626, filed on Mar. 31, 2021, now Pat. No. Des. 969,480.

(51) LOC (14) Cl. 03-01

CLAIM

The ornamental design for a bag, as shown and described.

DESCRIPTION

FIG. 1 is a top front right perspective view of a bag showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top front left perspective view thereof.

The broken lines in the figures show portions of the bag that form no part of the claimed design.

1 Claim, 8 Drawing Sheets
